UNITED STATES PATENT OFFICE.

HARRY A. DOUGLAS, OF BRONSON, MICHIGAN.

LOCK FOR ELECTRIC SWITCHES.

Application filed June 18, 1926. Serial No. 116,932.

My invention relates to devices, such as electric switches which employ member operating locks and member operating handles and resides in the provision of improved means for assembling the locks and handles with the casings for such devices.

In accordance with my invention, the handle is mounted to turn upon the casing and has a hub portion received in an opening 10 formed in the front end wall of the casing and a formation, such as a flange, upon the rear of and coacting with the front casing end wall to obstruct outward movement of the handle. The lock has a member, such as 15 a sleeve, at the opening in the front casing end wall and received in the handle hub, this lock member also having a formation, such as a wing or wings, also located upon the rear of and coacting with said front casing 20 end wall to obstruct outward movement of said lock member. Spring means are employed for pressing said lock member and handle forwardly to maintain these elements in assembly with the casing. Where switching mechanism is provided in the casing, one 25 circuit adjusting member thereof is coupled with the handle to be operated thereby and one circuit adjusting member is coupled with a key operated lock member that is 30 complementary to the aforesaid lock member. The switching mechanism includes contact effecting spring means that is desirably coupled for pressing the handle and the first aforesaid lock member forwardly for the 35 purpose stated.

I will explain my invention more fully by reference to the accompanying drawings showing an embodiment in conjunction with switching mechanism and in which Fig. 1 is a rear view of the switching mechanism taken on line 1—1 of Fig. 2; Fig. 2 is a sectional view on line 2—2 of Fig. 1; Fig. 3 is a sectional view on line 3—3 of Fig. 1; Fig. 4 is a front view of the switch, on a smaller scale; Fig. 5 is a view illustrating the assembly of a hollow lock member with the front casing end wall, this view being taken from the rear with parts removed; Fig. 6 illustrates the assembly of the closure 45 upon the rear of the casing with the casing; Fig. 7 is a perspective view of the tumbler barrel; Fig. 8 is a perspective view of the hollow lock member which receives the tumbler barrel and which is assembled with the 50 front casing end wall; Fig. 9 is a perspective view of the handle; Fig. 10 is a perspective view of the handle hub. The parts shown in the 55

view, with parts broken away, of the body of the casing and a portion of the mounting plate with which the casing is assembled; Fig. 11 is a sectional view on line 60 11—11 of Fig. 2; and Fig. 12 is a view showing the switch casing in section and parts within the casing in elevation.

The casing has a body portion 1 and a front end wall 2 preferably integrally 65 formed with the body portion. A closure 3, of insulating material, is assembled with the rear of the casing body by means of tongues 4 upon the casing body that are bent into notches 5 upon the closure 3. 70 This closure carries contacts 6 that may, for example, pertain to lighting circuits of automobiles, and contacts 7 that pertain to the ignition circuit. A ring 8 carries contacts 9 that are engageable with the 75 contacts 6. A plate 10 carries contacts 11 that are engageable with the contacts 7. The contacts 9 and 11 are formed upon the rear ends of spring barrels 12 and 13, these spring barrels housing springs 14 80 that project the plungers 15 and 16 forwardly into sockets 17 and 18 which are respectively formed in insulating rings 19 and 20. The springs 14 also press the contacts 9 and 11 rearwardly and the insulating rings 19 85 and 20 forwardly, the forward movement of these insulating rings being limited by their engagement with the front end wall 2 of the casing. This front casing end wall is formed with an opening which receives the 90 hub 21 of a handle 22. This handle has a flange 23 upon the rear of the front casing end wall 2 and pressed against this end wall by the springs 14 whereby the handle is maintained in assembly with the casing. 95 The handle hub is circular as is the opening in the casing end wall through which it is passed permitting the handle to be turned. The handle may be employed to control the lighting circuits of an automobile. Where 100 the switching mechanism is also employed to control an ignition circuit, the hub of the handle is hollow and may receive the hollow lock member 24 which is here shown as being received in the hollow hub of the handle. 105 This lock member is provided with wings 24' which are received between the lugs 25 which are struck inwardly from the front casing end wall. The springs 14 also press upon said wings to hold them against the front 110 end wall of the casing and fully within the handle hub. The springs 14 effect forward

pressure upon the handle and the wings 24 through the intermedium of the insulating rings which receive the plungers 15 and 16.

The ring 19 is connected with the handle by means of the prongs 26 upon the inner end of the handle hub, these prongs entering suitable recesses 27 upon the inner side of the handle hub. When the handle is turned, the ring 19 is turned to adjust the lighting circuits that are controlled by the contacts 6 and 9.

The ignition circuit is governed by a key operated tumbler barrel 28 which is in turning relation to the ring 20. This tumbler barrel contains tumblers 29 which are engageable within the slots 30 in the hollow lock member 23 when the key 31 is withdrawn after this key has turned the tumbler barrel to bring these tumblers into register with said slots. When the key is inserted, the tumblers are withdrawn from said slots whereafter the key is permitted to turn the tumbler barrel. When the tumblers are projected into the slots 30 the ignition circuit is locked open. When the tumblers are withdrawn from the slots when the tumbler barrel is thereafter turned, the ignition circuit is closed.

In assembling the parts, the handle is inserted from the rear of the casing into the position illustrated whereafter the hollow lock member 23 is positioned as shown, the rest of the parts following in obvious order.

Changes may be made without departing from the invention.

Having thus described my invention, I claim:

1. The combination with a casing having a front end wall formed with an opening therethrough, of a lock having a member at said opening and having a formation upon the rear of and coacting with said front casing end wall to obstruct outward movement of said lock member; spring means pressing forwardly upon said lock member to maintain it in assembly with the casing; a key operated lock member coacting with the aforesaid lock member; and mechanism within the casing and having a member coupled with said key operated member to be operated thereby.

2. The combination with a casing having a front end wall formed with an opening therethrough, of a lock having a hollow member in line with said opening and having a formation upon the rear of and coacting with said front casing end wall to obstruct outward movement of said lock member; spring means pressing forwardly upon said lock member to maintain it in assembly with the casing; a rotatable key operated tumbler barrel within the aforesaid lock member; a key operated tumbler within said tumbler barrel and coacting with said hollow lock member to hold said tumbler barrel.

barrel from turning; and mechanism within the casing and having a member coupled with said tumbler barrel to be operated thereby.

3. The combination with a casing having a front end wall formed with an opening therethrough; of a lock having a member at said opening and having a formation upon the rear of and coacting with said front casing end wall to obstruct outward movement of said lock member; a key operated lock member coacting with the aforesaid lock member; and mechanism within the casing and having a member coupled with said key operated member to be operated thereby, said mechanism including spring means that presses forwardly upon the first aforesaid lock member to maintain it in assembly with the casing.

4. The combination with a casing having a front end wall formed with an opening therethrough; of a lock having a hollow member in line with said opening and having a formation upon the rear of and coacting with said front casing end wall to obstruct outward movement of said lock member; a rotatable key operated tumbler barrel within the aforesaid lock member; a key operated tumbler within said tumbler barrel and coacting with said hollow lock member to hold said tumbler barrel from turning; and mechanism within the casing and having a member coupled with said tumbler barrel to be operated thereby, said mechanism including spring means that presses forwardly upon said hollow lock member to maintain it in assembly with the casing.

5. The combination with a casing having a front end wall formed with an opening therethrough; of a handle mounted to turn upon the casing and having a hub portion received in said opening and a formation upon the rear of and coacting with said front casing end wall to obstruct outward movement of the handle; spring means pressing forwardly upon said handle to maintain it in assembly with the casing; and mechanism within the casing and having a member coupled with said handle to be operated thereby.

6. The combination with a casing having a front end wall formed with an opening therethrough; of a handle mounted to turn upon the casing and having a hub portion received in said opening and a formation upon the rear of and coacting with said front casing end wall to obstruct outward movement of the handle; and mechanism within the casing and having a member coupled with said handle to be operated thereby, said mechanism including spring means that presses forwardly upon said handle to maintain it in assembly with the casing.

7. The combination with a casing having

5 a front end wall formed with an opening therethrough; of a handle mounted to turn upon the casing and having a hub portion received in said opening and a formation 50 upon the rear of and coacting with said front casing end wall to obstruct outward movement of the handle; a lock member at 55 said opening, this lock member having a formation upon the rear of and coacting with said front casing end wall to obstruct outward movement of said lock member; a 60 spring means pressing forwardly upon the aforesaid lock member and upon said handle to maintain these elements in assembly 65 with the casing; a key operated lock member coacting with the aforesaid lock member; and mechanism within the casing having one member coupled with said handle and another member coupled with said key operated lock member. 70

75 8. The combination with a casing having a front end wall formed with an opening therethrough; of a handle mounted to turn upon the casing and having a hub portion received in said opening and a formation 80 upon the rear of and coacting with said front casing end wall to obstruct outward movement of the handle; a hollow lock member in line with said opening, this lock member having a formation upon the rear 85 of and coacting with said front casing end wall to obstruct outward movement of said lock member; spring means pressing forwardly upon the aforesaid lock member and upon said handle to maintain these elements in assembly with the casing; a rotatable key operated tumbler barrel within the aforesaid lock member; a key operated tumbler with said tumbler barrel and coacting 90 with said hollow lock member to hold said tumbler barrel from turning; and mechanism within the casing and having a member coupled with said handle and another member coupled with said tumbler barrel. 95

9. The combination with a casing having a front end wall formed with an opening therethrough; of a handle mounted to turn

upon the casing and having a hub portion received in said opening and a formation upon the rear of and coacting with said front casing end wall to obstruct outward movement of the handle; a lock member at said opening, this lock member having a formation upon the rear of and coacting with said front casing end wall to obstruct outward movement of said lock member; a key operated lock member coacting with the aforesaid lock member; and mechanism within the casing having one member coupled with said handle and another member coupled with said key operated lock member, said mechanism including spring means that presses forwardly upon the first aforesaid lock member and handle to maintain these elements in assembly with the casing. 100

10. The combination with a casing having a front end wall formed with an opening therethrough; of a handle mounted to turn upon the casing and having a hub portion received in said opening and a formation 105 upon the rear of and coacting with said front casing end wall to obstruct outward movement of the handle; a hollow lock member in line with said opening, this lock member having a formation upon the rear 110 of and coacting with said front casing end wall to obstruct outward movement of said lock member; a rotatable key operated tumbler barrel within the aforesaid lock member; a key operated tumbler within said 115 tumbler barrel and coacting with said hollow lock member to hold said tumbler barrel from turning; and mechanism within the casing and having a member coupled with said handle and another member coupled with said tumbler barrel, said mechanism including spring means that presses forwardly upon said hollow lock member and handle to maintain these elements in assembly with the casing. 120

In witness whereof, I hereunto subscribe my name.

HARRY A. DOUGLAS.
